UNITED STATES PATENT OFFICE.

CHARLES E. TITCHENER, OF BINGHAMTON, NEW YORK, ASSIGNOR TO CRANDAL, STONE & COMPANY, OF BINGHAMTON, NEW YORK, A CORPORATION OF NEW YORK.

DESIGN FOR A CURTAIN-LIGHT.

47,146.

Specification for Design.

Patented Mar. 23, 1915.

Application filed January 4, 1915. Serial No. 529. Term of patent 14 years.

To all whom it may concern:

Be it known that I, CHARLES E. TITCHENER, a citizen of the United States, residing at Binghamton, in the county of Broome and State of New York, have invented a new, original, and ornamental Design for Curtin-Lights, of which the following is a specification, reference being had to the accompanying drawing, forming part hereof.

Figure 1 of the drawing is a front eleva-

tion of a curtain light, showing my new design, and Fig. 2 is a longitudinal section thereof.

I claim:—

The ornamental design for a curtain light, as shown.

CHARLES E. TITCHENER.
